UNITED STATES PATENT OFFICE.

GEORGE S. NEELEY, OF HARTFORD, ILLINOIS, ASSIGNOR OF ONE-HALF TO GRIFFIN WATKINS, OF ALTON, ILLINOIS.

SAFETY GUARD FOR PRESSES.

Application filed May 22, 1926. Serial No. 110,917.

This invention relates to new and useful improvements in safety guards for presses and particularly for leather presses.

In the history of the operation of embossing 5 presses, and particularly leather presses, there are recorded many instances of the press operators losing their hands or fingers due to the hazardous operations of such presses.

The primary object of the invention is to 10 provide a safety guard comprising automatically operable means which are powerful to bodily move the press operator away from the press, thereby providing assurance that the press operator is always clear of the working 15 jaws of the press during the closing operation of the press jaws.

Further objects of the invention are to 20 provide an automatic safety guard that is positive in its action and provides absolute safety to the operator.

Still further objects of the invention are to 25 provide a safety guard having a minimum number of working parts and requiring very little attention, thereby reducing the main- tenance expense to minimum.

Other objects of the invention are to provide a safety guard that is adjustable to regulate the throw of the safety bar with respect to the size of the operator so as to bodily 30 move any sized operator a safe distance from the jaws during the pressing operation.

Still other objects of the invention are to 35 produce a safety guard that is of simple construction, provides easy access to the working parts of the press and which is arranged so as to allow the use of materials of great strength, thereby providing a safety device that is reliable in operation and will not be- 40 come easily bent, broken, or rendered inoper- ative.

With these and other objects in view, my 45 invention consists in certain novel features of construction and arrangement of parts, hereinafter more fully described and claimed, and illustrated in the accompanying drawings, in which—

Figure 1 is a front elevational view of a 50 press showing the safety guard applied thereto.

Figure 2 is an end elevational view of same.

Figure 3 is an end elevational view of a modified form of my invention.

Figure 4 is an end elevational view of still another modified form of my invention.

Figure 5 is a detail cross sectional view 55 taken on line 5—5 of Figure 2.

Figure 6 is a cross sectional view taken on line 6—6 of Figure 2.

Figure 7 is a cross sectional detail view 60 taken on line 7—7 of Figure 2.

Figure 8 is a cross sectional view taken on line 8—8 of Figure 2.

Referring by numerals to the accompanying drawings, 10 indicates a press having a stationary jaw 11, a movable jaw 12, and front 65 and rear tables 14. In the operation of the press, work material, such as leather, is placed on table 14 and moved on to the jaw 12 by the operator whereupon the press is operated by suitable mechanism, not shown, to bring the 70 movable jaw 12 against jaw 11 and place the work positioned therebetween under pressure. In arranging the work on the movable jaw 12, the operator necessarily extends his or her hands between the jaws. Consequently, 75 if the press is operated prematurely or the operator is slow in withdrawing his hand from between the jaws, the hand or fingers will be caught between the jaws and crushed.

By the use of the safety guard herein disclosed, the operator is moved bodily a suitable distance from the press as soon as the latter is operated so that it is impossible for the operator to have his or her hands caught between the jaws, thus providing positive 80 means for insuring the safety of the operator. This safety guard comprises a horizontally disposed bar 15, preferably arranged in front and rear of the press at a suitable height so that when said bar is moved outwardly it will 85 bear against the chest of the operator and push the latter a suitable distance from the press so that the hands of the operator even if stretched forwardly the full distance will 90 be out of reach of the jaws. The ends of 95 each bar 15 are secured to one of the ends of a pair of vertically disposed arms 16 which are pivotally mounted at 17.

In the preferred form, this mounting consists of brackets 18 secured to the ceiling 100 above the press and supporting a horizontally disposed rod or pipe 19 on which are loosely disposed T-connections 20 which receive the upper ends of arms 16. In this manner a U-shaped member is formed, the horizontal portion of which when the press is inactive is disposed immediately in front of the table 14 and the upper ends of the vertical portions of 105

which are pivotally suspended from the ceiling with the U-shaped member occupying substantially vertical position.

A horizontally disposed rod or pipe 21 is mounted at its ends by means of T-connections 23 to the vertically disposed arms 16 a suitable distance from pivots 17, and loosely arranged on said rods are T-connections 24 of link members 25 which latter extend inwardly and downwardly toward the center of the press. The inner end of each member 25 is fixed to a T-connection 26 which is loosely arranged on a horizontally disposed rod or tube 27. Thus the movement of rod 27 in vertical plane will cause arms 16, through angularly disposed members 25, to swing on pivots 17. The extent of this swinging movement is controlled by the location of rod 21 relative to the respective pivots 17. To this purpose T-connections 23 are adjustable on arms 16 so that rods 21 may be moved toward pivots 17 to increase the arc of movement of bars 15, or vice versa. A set screw 28 is used to secure each T-connection 23 in adjusted position on arm 16.

Each link member 25 is provided with an extensible joint 25^a by means of which link 25 may be lengthened or shortened as desired to maintain arms 16 and bar 15 in proper positions relative to table 14. This joint preferably comprises a turn buckle or screw 29 having its ends in oppositely threaded engagement with sections 25^b, whereby by turning member 29 in proper direction, member 25 may be extended or shortened. A jam nut 30 serves to lock each end of member 29 with the respective section 25^b. Connections 26 are arranged in pairs which extend in opposite directions from member 27 to receive the ends of members 25 which converge toward the center of the press. The ends of member 27 are carried by connections 31 which latter are fixed to vertically disposed members 32 arranged on each side of the press and having their lower ends fixed to the respective sides of movable jaw 12 as indicated at 33.

The upper ends of members 32 are formed tubular and are open to receive and form telescopic engagement with the downwardly presented guides 34 which are secured to the ceiling and are disposed in axial vertical alignment with members 32. The ends of front bars 15 are tied together by transversely disposed side sections 35 having a telescopic joint 36 to provide for the relative swinging movements of bars 15. This telescopic joint is formed by forming each section 35 of two tubular members 37 and 38, respectively, one end of a rod 39 being fixed to member 38 and the opposite end of which rods extends into the other end of the oppositely disposed end of tubular member 37.

When the press is operated, jaw 12 is moved upwardly, thereby raising vertically disposed side bars 32, the latter being guided in their

vertical movement by guides 34. This elevates horizontally and longitudinally disposed members 27 which acts as a toggle joint for members 25, thereby causing vertically disposed rods 16 to swing outwardly away from the press as shown in dotted lines in Figure 2. In doing so, bars 15 bear against the upper part of the operator's body and move him or her bodily away from the press. The throw or outward movement of bars 15 is calculated so that when the operator is moved by said bars his outstretched hands will be a safe distance from the jaws of the press so that under no circumstances would be it possible for the operator's hand to be caught between the jaws. The throw or outward movements of bars 15 can be regulated to take care of different sized operators by adjusting the rods 21 with respect to pivots 17 and correspondingly adjusting link members 25.

As the vertical movement of member 31 is fixed, being the same as the movement of jaw 12, the shifting of T-connections 23 relative to pivots 17 will control the extent of outward movement of bars 15. In this manner bars 15 are positively operated in proper time relation with the actuation of the press and the safety guard is so arranged that it does not interfere with the operation of the press or the duties of the operator.

In the form shown in Figure 3, bars 16^a extend downwardly from bar 15^a and have their lower ends pivotally mounted at 41 on the floor of the press room. Links 42 are pivotally connected to the movable jaw 12 at 44 and to the bars 16^a at 45, thereby causing bars 15^a to swing outwardly with the upward movement of jaw 12. This form of construction is especially designed for use where it is not desirable or not practicable to mount the swinging bars from the ceiling.

In the modified form shown in Figure 4, bars 16 are actuated by links 46 pivotally interengaged at one of their ends with bars 16 and having their opposite or inner ends pivotally interengaged with a table 47 of a movable jaw 12^a as at 48, said pivotal points 48 being disposed to each side of the stationary jaw 11.

In the type of the press disclosed in this form, the size of table 47 is such that it is more convenient to mount the members connecting the movable jaws with the actuating mechanism of the swinging bars direct on to the table of said jaw.

A guard of my improved construction is so arranged that it does not interfere with or hamper the operator in tending to the press, and the operating connections of the guard are so disposed that they are out of the way of the operator so that there is no possibility for the operator's hands being caught therein and the adjustments or connections cannot be tampered with or changed, thereby making

the guard fool-proof and safe under all conditions.

The parts are of strong construction and are subjected to very little wear as the movements of the various parts are negligible, thereby reducing the danger of the mechanism getting out of order to minimum. The telescopic side bars 35 provide guards for the sides of the press so as to prevent accidental movement of the operator or other workman too close to the press, without, however, interfering with the access to the machine.

My improved guard is so constructed that it is not necessary to remove or disconnect the guard or any of its connections in making adjustments or minor repairs on the press, thereby eliminating the danger of the guard being left disconnected by the mechanic.

While I have shown and described the preferred form of my invention, it is obvious that minor changes in the size, form, and construction of the various parts of my invention may be made and substituted for those herein shown and described, without departing from the spirit thereof as expressed in the appended claims.

I claim:

1. An automatic safety guard for presses comprising in combination with a movable part of a press a system of pendulum arms arranged in pairs on each side of the press and oscillatory transversely of the press, horizontally disposed bars arranged in front of each end of the press and supported by each pair of said arms, and toggle mechanism connected to the opposite arms of said pairs of arms and operable by a movable part of the press for causing said bars to move laterally a suitable distance from the press to prevent access to the press during the closing operation of the movable press jaw.

2. A safety guard for presses comprising in combination with a movable part of a press arms pivotally suspended at points remote from said press, a link pivotally connected to each arm and to said movable part of said press for actuating said arms in co-relation with said press, and horizontally disposed bars carried by the free ends of said arms adjacent to each end of said press and movable laterally by said arms to bodily push the operator away from the press during the closing movement of the main working jaw.

3. A safety guard for embossing presses comprising in combination with a movable part of a press, oppositely spaced two pairs of arms pivotally mounted adjacent to said press, a horizontally disposed bar carried by the free ends of one pair of arms and normally disposed immediately in front of said press at a predetermined height with respect to the operator, means operable by said movable part of said press and connected to said arms for oscillating the latter, whereby said bars are actuated in an arc away from said press a

predetermined distance during the closing movement of the jaws of said press, and telescopic side bars arranged on each side of the press and connected to the respective arms.

4. A safety guard for presses comprising in combination with a movable part of a press, opposite two pairs of arms pivotally suspended from the ceiling of the press room, horizontally disposed bars arranged adjacent to each end of said press and fixed to said arms, said bars being movable laterally by said arms to bodily push the operator away from the press during the closing movement of the main working jaw, of said press, toggle joint mechanism connecting the respective pairs of pivoted arms, and connections between said toggle joint mechanism and a movable part of said press for actuating said arms and moving said bars to position the operator a definite distance away from the press during the closing movement of the jaws of said press.

5. A safety guard for presses comprising in combination with a movable part of a press, two opposite disposed pairs of arms pivotally suspended from the ceiling of the press room, horizontally disposed bars arranged adjacent to each end of said press and fixed to said arms, said bars being movable laterally by said arms to bodily push the operator away from the press during the closing movement of the main working jaw of said press, toggle joint mechanism connecting the respective pairs of pivotal arms, connections between said toggle joint mechanism and a movable part of said press for actuating said arms and moving said bars a definite distance away from the press during the closing movement of the jaws of said press, and means for adjusting the points of interengagement between said toggle joint mechanism and said bars to regulate the operative movements of said arms.

6. A safety guard for presses comprising in combination with a movable part of a press, opposed arms pivotally suspended from the ceiling of the press room, horizontally disposed bars arranged adjacent to each end of said press and fixed to said arms, said bars being movable laterally by said arms to bodily push the operator away from the press during the closing movement of the main working jaws of said press, toggle joint mechanism connecting the respective opposed arms, and connections between said toggle joint mechanism and said movable part of said press for actuating said arms and moving said bars to position the operator a definite distance away from the press during the closing movement of the jaws of said press, and means for guiding said toggle joint mechanism and the operating connection therefor.

7. In a safety guard for a press having a movable part, the combination of two pairs of spaced arms, each arm being pivotally

mounted at one end adjacent to and independently of said press; a horizontally disposed bar disposed immediately in front of and extending the full width of each end of said press at a predetermined height with respect to the operator; said bar having its ends secured to the free ends of the arms of one of said pairs of spaced arms; a member fixed to each side of said movable part; and a pair of links disposed on each side of said press

and having their inner ends pivotally connected to said member and having their outer ends pivotally connected to the corresponding arms of each pair for swinging said arms on their pivots and actuating each bar in an arc away from said press during the closing operation of the jaws of said press. ¹⁵

In testimony whereof I hereunto affix my signature this 12th day of May, 1926.

GEORGE S. NEELEY.
